ATTORNEYS.

UNITED STATES PATENT OFFICE.

ERNEST DAVIS, OF SYRACUSE, NEW YORK, ASSIGNOR TO THE PROSPERITY COMPANY INC., OF SYRACUSE, NEW YORK, A CORPORATION OF NEW YORK.

POWER-ACTUATING MECHANISM.

Application filed May 12, 1926. Serial No. 108,460.

This invention relates to power actuating mechanism particularly adapted for actuating the movable element of a pressing machine, which actuating mechanism is of the type shown in my pending application Sr. No. 671,568, filed October 29, 1923 and it has for its object a particularly simple and efficient control mechanism whereby two hands are required to control the flow of 10 motive fluid to the fluid motor or (which is in this instance a cylinder and a single acting portion,) during the power stroke and but one hand is required to control the actuation of the motor during its return stroke, 15 and then only a momentary actuation of the control means is required.

The invention consists in the novel features and in the combinations and constructions hereinafter set forth and claimed.

20 In describing this invention reference is had to the accompanying drawing, which is a diagrammatical view partly in section and partly broken away of an actuating mechanism embodying my invention.

25 This power actuating mechanism comprises, generally, a fluid operating motor as a cylinder, and a single acting piston movable in the cylinder, means for controlling the flow of motive fluid to and from the 30 motor or cylinder, including a feed conduit or feed line for the motive fluid as compressed air, a combined intake or exhaust pipe leading to the cylinder, a valve casing between the main feed conduit and the combined intake and exhaust pipe, combined intake and 35 exhaust valves therein normally arranged so that the intake valve is closed and the exhaust valve open, dual manual means for controlling the operating of the valves, and fluid operated means for holding the valves 40 in their operated position after the motor has been actuated by the motive fluid or air a predetermined distance, that is after the piston has travelled a predetermined distance in the cylinder or the mechanism actuated by the piston a predetermined amount, and a single manual for releasing the last mentioned fluid operated means so that the combined valve will return to its 45 normal position in which the intake valve is open and the exhaust valve closed so that air can exhaust from the cylinder through the combined intake and exhaust pipe, and the valve casing.

50 The fluid motor is here shown as a cyl-

inder and a piston movable in the cylinder and 1 designates the cylinder, 2 the piston therein having the usual rod 3. 4 is the main feed conduit for the motive fluid it having a regulating valve 5 therein. 6 is the 60 combined intake and exhaust pipe leading to the cylinder. 7 is the valve casing connecting the pipes 4 and 6. 8 is an intake valve movable toward and from the seat 9 therein; and 10 the exhaust valve movable toward 65 and from the seat 11 in the casing, the valves being connected to move as a unit by a stem 12. The pipe 6 communicates with the valve casing between the valves 8 and 10. The combined valves are normally held 70 with the intake valve closed and the exhaust valve open by a spring 13 and also by the air pressure from the pipe 4.

The dual manual means for operating the valves is here shown as hydraulic in character and consists of a pair of sylphons 14, 15 communicating through pipes 16, 17 with a pipe 18, which communicates with a sylphon 19 of a capacity equal to both of the sylphons 14, 15, the sylphon 19 operating 80 on a stem 20 which coacts with the lever 21, the lever acting on a plunger 22, which in turn thrusts against the valve 10. The lever 21 acts on the plunger 22 through an interposed lever 23 to be hereinafter described. 85 The actuation of either sylphon 14, 15 does not displace enough liquid in the system to actuate the sylphon 19 sufficiently to operate the valves 8 and 9, but the operation of either two of these sylphons 14, 15 merely 90 displaces the oil or fluid from one into the other. The depression of both the sylphons 14, 15 is required to compress the fluid or oil in the sylphon 19 so that it acts to actuate the lever 21. This form of dual manual 95 means forms the subject matter of my Patent No. 1,549,459, August 11, 1925.

When both sylphons 14, 15, are held depressed so that air is free to flow in to the cylinder, the operator must hold the 100 sylphons compressed until the piston has moved a predetermined distance. The means for holding the valves 8 and 11 in their operated position after the piston has moved a predetermined distance, as here 105 shown comprises a fluid operated means which receives motive fluid after the piston has traveled a predetermined distance, this fluid operated means being here shown as a diaphragm 24 located in a diaphragm 110

chamber 25, which is connected by a pipe 26 to the cylinder 2 and is joined to the cylinder 2 through a port 27 located to be uncovered by the piston when the piston 5 has nearly completed its power stroke. Obviously when the port 27 is uncovered air from the cylinder will pass to the diaphragm chamber and actuate the diaphragm from its position shown in the drawings in 10 full lines to the dotted line position and thus actuate a plunger 28 acting with the lever 23. This lever 23 is pivoted at 29 between its ends so that when the plunger 28 is actuated this lever 23 thrusts against the 15 plunger 22 of the exhaust valve 11 and holds the exhaust valve in its closed position and hence the intake valve 8 in its open position.

In order to permit the valve 8 to close and the exhaust valve 11 to open in order to exhaust 20 the motive fluid from the cylinder, a single manual means is provided to exhaust the air from the diaphragm chamber 25, this means including a valve located in the pipe 26. 30 designates the valve in a valve casting 31 in the pipe 26, the valve 30 being normally held in closed position by a spring 32. This valve is operated by a manually 25 operable sylphon 33 connected by a pipe 34 to a sylphon 35, which in turn acts upon 30 the stem 36 of the valve 31, obviously depressing of the sylphon 33 will cause the sylphon to open the valve 30 so that the air 35 exhausts from the diaphragm chamber 25 whereby the spring 33 is free to close the intake valve 8 and open the exhaust valve 11 and also through the plunger 11, the lever 23 returns the sylphons 19, 14 and 15 to their normal position, if they have not assumed 40 their normal position under their own resiliency.

What I claim is:—

1. A power actuating mechanism comprising a fluid operated motor, means for controlling the flow of motive fluid to and from the motor including a feed conduit for the motive fluid, a combined intake and exhaust pipe leading to the cylinder, a valve casing 45 between the feed conduit and the intake pipe, combined intake and exhaust valve in 50 said casing arranged so that the intake valve

is normally closed and the exhaust valve normally opened, dual means for operating said combined valves to open the intake and close the exhaust, and fluid operated means operated by the pressure of the motive fluid, 55 a pipe connecting said fluid operated means and the fluid operated motor to receive motive fluid therefrom, a normally closed valve in said last mentioned conduit, and a single manual for opening the last mentioned valve. 60

2. A power actuating mechanism comprising a fluid operated motor and means for controlling the flow of fluid to and from the motor including manually operable combined intake and exhaust valves normally 65 in a position in which the exhaust valve is open and the intake valve closed, means for holding and returning the valves to their normal position, pressure operated means controlled by the motor for holding the combined valves in their operated position against the action of the returning means and a separate manually operable valve for controlling the flow of fluid to and from the pressure operated means. 70

3. A power actuating mechanism comprising a fluid operated motor including a cylinder and a piston, means for controlling the flow of fluid to and from the motor including a feed conduit for a motive fluid, 80 an intake and outlet pipe leading to the cylinder having combined intake and exhaust valves therein arranged with the intake normally closed and the exhaust valve normally open and means tending to return 85 and hold the valves in their normal position, pressure operated means for holding said valves in their operated position against the returning means and a conduit connecting the pressure operated means and the fluid 90 motor whereby the pressure of the motive fluid in the motor is transferred through said conduit to the pressure operated means to operate it and a normally closed manually operable exhaust valve in said conduit. 95

In testimony whereof, I have hereunto signed my name, at Syracuse, in the county of Onondaga and in the State of New York, this 26th day of April, 1926.

ERNEST DAVIS.
